UNITED STATES PATENT OFFICE.

HENRY ROSIER, OF LOWELL, MASSACHUSETTS.

AUTOMATIC FIREARM.

Application filed December 3, 1923. Serial No. 678,302.

To all whom it may concern:

Be it known that I, HENRY ROSIER, a citizen of the United States, residing at Lowell, in the county of Middlesex and State of 5 Massachusetts, have made a certain new and useful Invention in Automatic Firearms, of which the following is a specification.

The invention has relation to automatic firearms, having for its object the provision 10 of simple and efficient operating mechanism for the same. Other objects and advantages will hereinafter appear.

The invention consists in the novel construction and combinations of parts, as set 15 forth in the appended claims.

In the accompanying drawings, illustrating a preferred form of the invention, Figure 1 is a side view of the invention; Figure 2 is a central longitudinal section of the 20 same, with the parts in normal position ready for firing; Figure 3 is a similar fragmentary view, with the parts in position after firing has taken place; Figure 4 is a similar view with the parts in the position taken after 25 the recoil has taken place but before the breech block has been returned to normal position. In these drawings the numeral 1 designates a sliding breech block, held normally against the barrel 2 by a recoil 30 spring 3 and having mounted therein a firing pin 4, held in rearward position by a spring 5. In rear of and below the barrel is located a removable magazine 6, having a spring follower 7 and provided with side retaining 35 flanges 8 at its top margin. The ejector is shown at 9. All these parts operate in the well known manner, in cooperation with the mechanism of the lock, to utilize the recoil in automatic firing.

40 The lock is located in rear of the magazine and comprises a hammer 10, a locking cam 11 and a trigger 12 having a rearward pivoted arm 13. The hammer is pivoted at 14 and includes a striking face 15 having a 45 cam extension, a locking tooth 16 and a nose 17. Spring 17* tends to throw the striking face 15 of the hammer toward firing pin 4, this tendency being normally resisted by engagement of locking tooth 16 with a tooth 50 18 of locking cam 11. Cam 11 is pivoted at 19 and provided with a face 20 designed to lie normally in contact with the rear end of trigger arm 13. Spring 21 presses cam 11 toward this normal position. The trigger is 55 pivoted at 22 and has a rear shoulder 23, arm 13 being pivotally mounted thereon at

24, below pivot 22. A spring 25 lies between arm 13 and shoulder 23 and acts to hold shoulders 26 and 27 of the trigger and arm normally out of contact. A safety lock pin 60 28 is adapted for sliding operation into and out of contact with the shoulder 23, the exterior portion of said pin projecting in rear of the trigger guard, where it is not liable to be accidentally displaced. 65

The operation of the parts comprising the lock is as follows:

The trigger 12 being pressed, arm 13 thereof will trip the locking cam 11 and thus release hammer 10, which will be brought 70 against the firing pin 4 by spring 17*. In this movement nose 8 of the hammer will depress trigger arm 13, against the tension of its spring 9, bringing shoulder 27 against shoulder 26 and throwing the trigger forward into normal position, against the finger pressure, thus allowing the locking cam 11 to resume its original position, under the influence of spring 21. The cartridge having 75 been exploded, the recoil carries the breech 80 block 1 backward against the hammer, camming the latter over to cocked position, in which it is relocked by cam 11, and arm 13, released by the hammer, will rise to its first position, under the influence of spring 85 25, all these movements taking place before the muscular reaction draws the trigger back to firing position. Parts 10, 11, 12 and 13 being now in their first position, and the finger pressure becoming again effective, the 90 hammer will again be tripped, recoil spring 3 having meanwhile returned breech block 1 to forward position.

The automatic return of the trigger to forward position is of service in signaling the 95 completion of each shot, and in initiating the release of the trigger at the proper moment when it is desired to cease firing.

I claim:

In automatic firearms, a sliding breech 100 block carrying a firing pin, a locking device, a hammer normally restrained by said device, and trigger mechanism including a member normally lying in contact with said hammer and with said locking device and operable to release the hammer from said device, said hammer adapted when released to throw said member out of contact with the locking device. 105

In testimony whereof I affix my signature.

HENRY ROSIER,
